UNITED STATES PATENT OFFICE.

AUGUSTE PACHE, OF NEW YORK, N. Y.

SPARK-PLUG-CONTROLLING DEVICE FOR INTERNAL-COMBUSTION ENGINES.

1,358,459.

Specification of Letters Patent.

Patented Nov. 9, 1920.

Application filed April 26, 1918. Serial No. 230,976.

To all whom it may concern:

Be it known that I, AUGUSTE PACHE, a subject of Switzerland, residing in the city of New York, borough of Manhattan, county and State of New York, have invented a certain new and useful Spark-Plug-Controlling Device for Internal-Combustion Engines, of which the following is a specification.

10 The invention is designed for use on aeroplanes, automobiles, boats and all gasolene and gas motors. The apparatus is so placed as to be controlled by the driver from his seat and can be used in conjunction with 15 any internal combustion engine, to allow of the cleaning of the spark plug at the will of the chauffeur or driver.

The object of the invention is to provide 20 means operable from the driver's seat, to allow of the selective operation of any particular spark plug of the internal combustion engine, by which the vehicle is propelled, to be individually operated by the driver for the purpose of allowing the compression or burning gases from the cylinder 25 to be exhausted through the plug, to free the plug from carbon deposits, dirt or oil. A further object of the invention is to provide a simple construction for carrying out 30 the first enumerated object and to so organize the parts that the electrode of any particular plug, or the entire plug itself, may be readily removed without requiring dismantling of any of the operating parts 35 of the device.

The drawings illustrate the preferred, practical embodiment of the invention, but it will be understood it is not confined to the specific structure shown, the same being typical, but not exclusive, of the forms in which the invention may be embodied.

In the drawings, Figure 1 is a side elevation of the invention as applied to the ordinary type of eight cylinder engine;

Fig. 2 is a section on line 2-2 of Fig. 1;

Fig. 3 is a top plan view;

Fig. 4 is a fragmentary perspective view;

Fig. 5 is a cross-section on line 5-5 of Fig. 1; and

Fig. 6 is a fragmentary view of the dashboard setting forth the different positions for cutting out the spark plugs.

Referring to the drawings, 10 indicates a plurality of spark plugs, one of which is associated with each cylinder 11 of an internal combustion engine. The plugs are

of the general character disclosed in my prior Patent No. 1,242,367 dated October 9, 1917, and my co-pending application Serial No. 163,324 filed April 20, 1917, in that each plug is provided with a longitudinal blow-off and priming passage through which extends a movable and removable pin 26, serving the dual purpose of an electrode, and a means for normally sealing the blow-off passage.

Mounted on the engine are standards 12, having pivotal connections 13 with carrier arms 14, on the outer ends of which are journals 15 carrying a shaft 21. Collars 23 preclude the shaft 21 from longitudinal movement in the journals 15. Shaft 21 is polygonal in cross-section, and is here shown as pentagonal, to allow of its being normally locked against inadvertent rotation by spring clips 17, carried by a rod 16, supported at its opposite ends in arms 14.

Mounted on shaft 21 is a plurality of cams 22, here shown as spring pressed rollers. Each roller is precluded from longitudinal movement on shaft 21 by washers 29 and cotter keys 28, as shown in Fig. 4. One of these cams is positioned to coöperate with each spark plug in such manner as to engage with the upper end of the movable electrode 26 to force said electrode down to its seat or to allow it to be raised so as to let the cylinder exhaust through the plug. Springs 18 serve to normally maintain the cams in co-operative relation with the plugs through the maintenance of the arms 14 in the full line operative position shown in Figs. 4 and 5. But, if it is desired to remove a plug, or one or more electrodes 26, the arms 14, may be bodily shifted on pivot connections 13 against tension of springs 18 into the dotted line positions of Figs. 4 and 5, to allow of free access to the plugs. When the shaft is in this inoperative position, the electrodes 26 may be readily withdrawn as shown in dotted lines in Fig. 5, to allow of manually cleaning or renewal of the same.

It will of course be understood that one rock shaft 21 is associated with each bank of cylinders in case the invention is embodied in an engine of the V-type, as shown in the drawings, and, that in vertical engines having dual ignition, i. e., two plugs in each cylinder, there would be one rock-shaft with its described adjuncts associated with each series of plugs.

Aside from the bodily oscillatory move-

ment of each shaft 21 into and out of operative position, said shaft is adapted to be rocked by means of a handle 24, fixed thereto, to present different portions of the cams 5 22 to the plug electrodes 26. The several cams are set on the shaft in different relation so that, as the shaft is rocked, the low points of the cams may be successively presented to the successive electrodes, for 10 the purpose of allowing the exhausting of any particular cylinder through the plug.

In practice, the shaft 21 is made sufficiently long to project through the dash whereby the handle 24 is within easy access 15 of a chauffeur or driver, and, may be manipulated by him at any time to allow of the cleaning of the plugs without necessitating his leaving his seat in the car.

The present invention may be used as 20 shown and described on any type of internal combustion engine employing spark plugs, irrespective of the number of cylinders, it being understood that there will be as many cams 22 provided as there are plugs. Very 25 good results however may be obtained through the conjoint operation of the device of this invention and the trouble locating device of my co-pending application No. 230,975, since, if it is found through such 30 locating mechanism that the trouble is due to a short circuit at a plug, the device of the present invention may be manipulated to blow out such plug, and, if the short circuit was due to carbon, dirt or oil, the trouble 35 will be rectified immediately.

Having thus fully described my invention,

what I claim as new, and desire to secure by Letters Patent, is:

1. In an engine, a plurality of spark plugs, each of which is provided with a blow-off passage, and a valve for controlling said passage, in combination with controlling means common to a plurality of plugs for selectively controlling the operations of the blow-off valves. 40 45

2. In an engine, a plurality of spark plugs provided with valved blow-off outlets, and means for selectively controlling all of said outlets from a distant point.

3. In an engine, a plurality of spark plugs 50 provided with valved blow-off outlets, and unitary means for selectively controlling the outlets of all of said plugs.

4. In an engine, a plurality of spark plugs provided with valved blow-off outlets, means 55 associated with each plug for normally seating its valve, and controlling means, common to all the valve seating means, for allowing of the selective releasing of said valves, whereby any particular plug may be blown 60 out to the exclusion of the remaining plugs.

5. An internal combustion engine embodying a plurality of cylinders, each of which is provided with a spark plug having a movable electrode embodying a valve adapted to 65 close the blow-off passage through the plug, and manually operable means for selectively controlling the operations of said electrodes from a distant point.

In testimony whereof, I have signed my 70 name to this specification.

AUGUSTE PACHE.
